[57] CLAIM

The ornamental design for an adjustable, over-wall hanger, as shown and described.

DESCRIPTION

FIG. 1 is a front elevational view of an adjustable, over-wall hanger showing my new design;

FIG. 2 is a rear elevational view;

FIG. 3 is a right side elevational view, the left side elevational view being a mirror image;

FIG. 4 is a top plan view;

FIG. 5 is a bottom plan view; and,

FIG. 6 is a perspective view from the front, top and right side.

FIG. 1

FIG. 2

FIG. 3

FIG. 4

FIG. 5
